(57) **CLAIM**

I claim the design for a bottle, as shown.

DESCRIPTION

FIG. 1 is a front view illustrating a bottle of my design;

FIG. 2 is a rear view thereof;

FIG. 3 is a left side view thereof;

FIG. 4 is a right side view thereof;

FIG. 5 is a top view thereof.

FIG. 6 is a top view thereof; and,

FIG. 7 is a bottom view thereof.

The stippling applied to the cap portion of the bottle represents a contrasting material than that of the body portion of the bottle.
